United States Patent

Des. 240,669
Patented July 20, 1976

240,669

BUTTONER

Clyde H. Pifer, R.R. 1, Box 379, Devine, Tex. 78016

Filed Oct. 24, 1974, Ser. No. 517,638

Term of patent 14 years

Int. Cl. D28—99

U.S. Cl. D86—10 A

FIG. 1

FIG. 2

FIG. 6

FIG. 3

FIG. 7

FIG. 4

FIG. 5

FIG. 1 is a top perspective view of a buttoner showing my new design;

FIG. 2 is a side elevational view thereof;

FIG. 3 is a bottom plan view thereof;

FIG. 4 is an opposite side elevational view of FIG. 2;

FIG. 5 is a top plan view thereof;

FIG. 6 is a left end elevational view of FIG. 5; and

FIG. 7 is a right end elevational view of FIG. 5.

I claim:

The ornamental design for a buttoner, as shown.
